UNITED STATES PATENT OFFICE

ATHERTON B. NICHOLS, OF HASTINGS, MINNESOTA.

SHOCKING DEVICE.

1,174,756.

Specification of Letters Patent.

Patented Mar. 7, 1916.

Application filed November 18, 1914. Serial No. 871,915.

To all whom it may concern:

Be it known that I, AETHERTON B. NICHOLS, a citizen of the United States, resident of Hastings, county of Dakota, 5 State of Minnesota, have invented certain new and useful Improvements in Shocking Devices, of which the following is a specification.

My invention relates to corn shocking 10 appliances and the object of the invention is to provide a device that is easily portable from place to place in the field, can be easily and quickly set up in the shocking position, and as readily removed when the shock is 15 completed.

The invention consists generally in a shocking device having a leg adapted to rest upon the ground and provided with means for gripping or clamping the core 20 of the shock to hold it in an upright position while the bundles are being placed around it.

Further the invention consists in a device having means for clamping and squeezing 25 the bundles composing the shock together preparatory to binding them.

In the accompanying drawings forming part of this specification, Figure 1 is a view illustrating the shocking device in use, Fig. 30 2 is a detail view of one end of the device, showing the clamping means, Fig. 3 is a plan view of the same, showing the flexible means for clasping the core of the shock, Fig. 4 is a perspective view of a modified 35 construction.

In the drawing, 2 represents the leg of the shocking device, preferably of wood, corresponding substantially in length and size 40 to a pitch fork handle and having a lower tapered end to rest upon the ground. At the upper end of the leg is a metallic cap 3 fitting over the end of the leg and provided with a shank 4 extending outwardly at such an angle to the cap that when the device 45 is set up for use the shank will be substantially horizontal. The outer end of the shank has an offset therein forming a recess 5 in which a latch 6 is slidable between the bottom of said recess and a guide 7, 50 and a tripping cord 8 is attached to said latch and extends down to a point on the leg within convenient reach outside the shock. A sheave 9 is mounted in the wall of the shank and a cord 10 passes around 55 said sheave and has a loop 11 at its free end that is adapted to enter a transverse slot

12 formed in the shank 4 in the path of the latch 6, so that when the loop is inserted into the slot and engaged with the latch, the cord 10 will be temporarily secured and 60 when passed around a bundle may grip it firmly. Any suitable means may be provided for taking up the slack in the clamping cord, but I prefer to provide a windlass device 13 mounted on the leg 2 and 65 having an operating crank 14 by means of which the windlass can be wound up and the desired tension put on the cord. This windlass is preferably provided with the well known winding spring by means of 70 which the cord is normally kept in its wound position on the drum. I have not thought it necessary to illustrate the details of this drum, as I make no claim broadly to its construction. 75

To use the device, I preferably stand two bundles on end, with their butts a suitable distance apart to form two of the legs of the tripod, while the shocking leg forms the third one. The shank is held against 80 the upper portion of the bundles, as they lean against one another, and the free end of the clamping cord is passed around the bundles and its loop inserted into the slot 12 and engaged with the locking latch. The 85 windlass or other take-up device is then operated to draw the cord firmly around the two bundles and clamp them in their upright position. These bundles now form the core of the shock, which is completed 90 by stacking bundles around the core in the usual way. When the desired number of bundles is placed around the core, the clamping cord is released by withdrawing the 95 latch 6 and the shank withdrawn from the shock with the clamping cord, and then the cord may be placed around the entire shock and the windlass device operated to draw the tops of the bundles snugly around the 100 cord and hold them while the shock is tied by binding twine or other suitable means. The shocking device thereby serves two functions,—it forms a leg for supporting the core of the shock while the bundles are stacked around it, and clamps the tops of 105 the core bundles securely and when removed from the core, is utilized as a means for drawing the tops of all the bundles composing the shock into a compact form and holding them while they are bound together. 110

In Fig. 4 I have illustrated a modified construction, which consists in providing two

legs 15, pivoted together, and having jaws 16 in the form of tongs for gripping the sides of the bundles and holding them securely when the legs are thrust into the 5 ground. When these legs are lifted out of the ground, the jaws may be swung apart to allow them to be pulled out of the shock.

I do not wish to be confined in this application to the latch or locking means for 10 fastening the end of the cord to the upper portion of the leg or to the means for taking up the slack in the cord, as in various ways these features of the device may be modified and still be within the scope of my 15 invention.

I claim as my invention:

1. A shocking device comprising a leg to rest in an inclined position with one end on the ground, its other end having an ob- 20 tuse angled extension to rest transversely against the bundles which are to form the core of the shock, flexible means carried by said extension between which and said ex- tention the core may be clamped, a latch 25 mounted on said extension for holding one end of said flexible means, means carried by said leg for drawing said flexible means taut around the core, and means for releasing the latch when the core has been sur- 30 rounded by bundles to complete the shock.

2. A shocking device comprising a leg to rest in an inclined position with one end on the ground, its other end having an ob- 35 tuse angled extension to rest transversely against the bundles which are to form the core of the shock, means between which and said extension the core may be clamped, said means being removable with said extension after the core has been surrounded by bundles to complete the shock.

3. A shocking device comprising a leg to rest in an inclined position with one end on the ground, its other end having an extension to rest transversely against the bundles which are to form the core of the shock, 45 means carried by said extension between which and said extension the core bundles may be clamped, said leg and the core bundles forming a tripod against which the outer bundles are leaned, said extension and said clamping means being mounted for removal after the core has been surrounded by bundles to complete the shock.

In witness whereof, I have hereunto set my hand this 2d day of November, 1914. 55

ATHERTON B. NICHOLS.
